UNITED STATES PATENT OFFICE

WILLIAM I. RAVERT, OF HAZLETON, PENNSYLVANIA, ASSIGNOR TO A. W. DRAKE MANUFACTURING COMPANY, OF HAZLETON, PENNSYLVANIA, A CORPORATION OF PENNSYLVANIA

TOY FENCE

Application filed December 27, 1928. Serial No. 328,796.

This invention relates to toy fences and aims to provide an improved sectional fence that can be stamped out of sheet metal, which can be easily assembled or dismantled. The main idea is to provide a sturdy and ornamental fence adapted to be used around Christmas trees and window and other displays, and having special provision for receiving a series of small electric lamps on the fence posts.

In the accompanying drawing,

Fig. 1 is a fragmentary front elevation of a fence embodying the invention;

Fig. 2 is a front elevation of one section or panel of the fence;

Fig. 3 is a sectional view taken on the line 3—3 of Fig. 1;

Fig. 4 is a sectional view taken on the line 4—4 of Fig. 2; and

Fig. 5 is a sectional view taken on the line 5—5 of Fig. 1.

Referring particularly to the selected embodiment of the invention shown in the drawing, the fence comprises separable, ornamental panels 10 and posts 11 made of sheet metal stampings. The posts have special provision for receiving small lamp sockets 12 such as are used in ordinary Christmas tree sets, so that the lamps 13 also serve as ornaments.

Herein, the panels are shown as being substantially rectangular and having perforations to produce the desired ornamentation. The upper and lower edges are rolled or bent to provide tubular reenforcing beads 14 to prevent the thin sheet metal from bending laterally. Also, the upper tubular bead is adapted to receive and conceal the lamp cord between posts. The ends of the panels are each provided with a pair of attaching ears 15 to engage a post.

If desired, one or more gate panels 16 may be secured between two of the posts, and when attached to only one of the posts, the ears 15 act as a hinge on which the gate may swing. As shown in Fig. 1, the single gate panel is quite similar to the other panels, the only difference being in the ornamentation and the length. The upper edge is shown as being rounded and curled over so that it

also provides a channel or conduit for the lamp cord.

The posts 11 are shown as being made of three simple sheet metal stampings. One is a cup-shaped base or pedestal 17 and the other two are complementary, substantially semi-cylindrical sections 18, each having two or more ears 19 at its lower end inserted through slots in the base and bent over to hold them assembled on the base. The side edges of the sections 18 present radial abutting flanges 20, one crimped over the edge of the other to prevent them from separating (Fig. 5). These flanges have slots or perforations 21 to receive the ears or tangs 15 of the panels.

To provide receiving pockets or receptacles for the small lamp sockets 12, the upper ends of the posts are open, and present a reduced neck portion 22 and an ornamental dome or cap portion 23. The sections are spaced apart at the dome to provide opposed slots 24 to receive the lamp cords leading to the bottom of the lamp socket 12. It will thus be seen that the sockets fit snugly in the pockets 24 and their upper exposed ends, which are usually beaded, also contribute to the ornamental appearance of the posts. It is understood that the lamp sockets are connected in series as usual and as many lamps as there are posts may be employed.

From the foregoing description, it will be seen that the fences may be made very cheaply of relatively thin sheet metal and that all of the parts can be cut and stamped out very rapidly. Moreover, sets of the panels and posts may be packed in small cartons for shipment, and they are very easily assembled. Any convenient number of the units may be used to produce fences of any shape or outline, the ring-shaped ears on the panels permitting them to swing about the posts through an angle of approximately 180 degrees.

Obviously, the present invention is not restricted to the particular embodiment thereof herein shown and described.

What I claim is:

1. A toy fence of the class described comprising sheet metal tubular posts each having

an ornamental cap portion presenting a pocket for an electric lamp socket and wire receiving slots on opposite sides; and sheet metal panels having curled over reinforcing edges to receive and conceal the lamp cord between posts.

- 5 2. A toy fence of the class described comprising sectional, sheet metal posts each having opposite radial flanges presenting vertical slots; sheet metal base members secured to the posts; ornamental cap portions presenting pockets for electric lamp sockets; and panels having horizontally curved ears detachably secured in said slots.
- 10 3. In a toy fence of the character described, a tubular sheet metal post having a cup-shaped, stamped out base portion; a pair of complementary stamped out, substantially semi-cylindrical sections each having a radial flange; said flanges being crimped and secured together and presenting vertical panel securing slots; and a substantially dome-shaped portion at the top of the post providing a pocket to receive an electric lamp socket.
- 15 25

In testimony, that I claim the foregoing as my own, I have hereto affixed my signature.

WILLIAM I. RAVERT.
